CLAIM

I claim the ornamental design for a retaining device for a media disc, as shown and described.

DESCRIPTION

FIG. 1 is a top plan view of a retaining device for a media disc showing my new design;

FIG. 2 is an enlarged top plan view thereof;

FIG. 3 is a perspective view of FIG. 2; and,

FIG. 4 is an enlarged perspective view of an alternate embodiment of the design shown in FIG. 1; the top plan view being identical to FIG. 2.

The broken lines showing a disc tray in FIG. 1 illustrates the environment in which the design resides. The broken lines and circles directly on the surface of the claimed design define the boundaries of the claim with the lines themselves and the portions within them forming no part of the claim.
